UNITED STATES PATENT OFFICE.

EDWARD S. POMEROY, OF SPRINGFIELD, MASSACHUSETTS, ASSIGNOR TO SMITH & WESSON, OF SPRINGFIELD, MASSACHUSETTS, A VOLUNTARY ASSOCIATION UNDER DECLARATION OF TRUST.

AUTOMATIC PISTOL.

Application filed June 27, 1921. Serial No. 480,805.

To all whom it may concern:

Be it known that I, EDWARD S. POMEROY, a citizen of the United States of America, residing in Springfield, in the county of 5 Hampden and State of Massachusetts, have invented certain new and useful Improvements in Automatic Pistols, of which the following is a specification.

This invention relates to automatic pistols 10 or other firearms of the recoil-operated type, wherein the back-pressure of the gases due to the explosion forces back the breech block and thereby ejects the empty shell, re-cocks the arm, and reloads it ready for the 15 next firing. It further relates to such firearms which have a sliding barrel which on firing participates in the first portion of the recoil movement and is then stopped, while the breech block continues the recoil movement and accomplishes the ejection, recocking and reloading. In such arms the recoil 20 of the movable breech portion is taken up against an actuating or reaction spring which, when the recoil is spent, moves the breech portion forward to reload the arm by introducing a fresh cartridge from the magazine into the barrel. The invention further relates to automatic pistols wherein the breech block or bolt is normally connected 25 to a breech slide or housing, the two moving together in the automatic recoil and reaction movements, but being separable in order that the breech block may be retracted manually for the initial loading of the arm. 30 The present invention provides an automatic pistol or analogous firearm comprising a frame, a sliding barrel, a breech slide which is initially locked to the barrel and is set free at any suitable point in the recoil movement, and a breech block which is normally locked to the breech slide. The invention 35 provides an improved breech lock for preliminarily uniting the barrel and breech slide, and for disconnecting them and setting the breech slide free at the end of the preliminary retractile movement of the barrel. 40 The construction will be made apparent with reference to the accompanying drawings, which show the preferred embodiment 45 of the invention, and in which—

Figure 1 is a side elevation showing the breech slide in its retracted position in full lines, and in its normal position in dotted lines;

Fig. 2 is a front end elevation; 55 Fig. 3 is a vertical longitudinal mid-section, the barrel and breech lock being in elevation, and showing the parts in the position of rest ready for firing;

Fig. 4 is a transverse section on the line 60 4—4 in Fig. 3;

Fig. 5 is a similar section showing the breech slide and breech block in their instantaneous position at the end of the recoil movement; 65

Fig. 6 is a side elevation of the barrel;

Fig. 7 is an end elevation thereof;

Fig. 8 shows the breech lock detached, in three views, respectively a plan, side elevation, and front elevation. 70

Referring to the drawings, the pistol shown is, in general, of the well known Smith & Wesson type of automatic pistol. A is the barrel, and B is the main frame which includes the hollow stock or grip C 75 within which the magazine (not shown) is inserted in the usual manner. The breech block D is mounted to slide in the usual breech opening E, and is normally locked by a catch F to the breech slide G which is 80 formed as a sliding housing or hood overlying the barrel and stock and normally pressed forward by an actuating spring H which is confined within a chamber in the breech slide, pressing forward against the 85 solid front wall 10 thereof and rearwardly against a lug 11 projecting upwardly at the rear of the barrel A. The catch F may be of the construction shown in Patents No. 1,038,971, or 1,181,416 to J. H. Wesson. The 90 forward movement of the breech slide G, when disconnected from the breech block, is limited by a stop pin 12 which may be depressed for dismounting the arm. The firing mechanism shown is that commonly used 95 in the Smith & Wesson automatic, comprising a trigger L, a hammer J, and a firing pin I, the hammer being set by a sear K which is disengaged by the operation of the trigger. The details of this mechanism 100 being well understood in the art, and having no relation to the present invention, need not be described.

According to the present invention, the barrel A, instead of being fastened to the 105 frame B (as has been usual in the Smith & Wesson automatic) is mounted to have a limited sliding movement on the frame. In

the construction shown, the barrel slides in a semi-cylindrical recess 13 in the frame, and is engaged by a semi-cylindrical recess 14 on the under side of the saddle-shaped breech 5 slide G (see Fig. 2). The movement of the barrel is limited to the distance between a shoulder 15 on the barrel (Fig. 6) and a shoulder 16 on the frame (Fig. 3), a spring 17 serving to press the barrel forward. In 10 the preferred construction shown, the spring 17 is housed in a chamber formed in a lug 19 carried by the barrel, and presses against a plunger 18 which bears against the shoulder 16. The barrel has a projection 20 15 which carries the breech lock M shown separately in Fig. 8.

The breech slide G is constructed generally as heretofore, having the usual internal longitudinal ribs and grooves 21 having sliding engagement with the usual external grooves and ribs 22 on the main frame (Figs. 1 and 2). In addition, it is formed on opposite sides with notches 23 (see Fig. 1) for engagement (in the position shown 25 in dotted lines in Fig. 1) with the opposite locking lugs 24 of the lock M, whereby in the normal position ready for firing, the slide G is locked to the barrel. The lock M has any suitable engagement with the barrel A, that shown being by a vertical recess 25 making a close working fit with the vertical sides of the projection 20 on the barrel. The lock M has also an oblique engagement with the frame B. For this purpose the 30 frame has a milled-out socket 26 the sides of which have oblique grooves 27 milled in them, and the lock M has on its opposite sides oblique ribs 28 which slide in these grooves. It results from this construction 35 that as the barrel moves backward from its position shown in Fig. 3, the lock M descends by sliding down these inclined grooves, and thereby lowers its locking lugs 24 until at the end of the prescribed movement of the barrel these lugs descend sufficiently far to disengage from the notches 23, so that at the instant when the barrel is 40 stopped by the contact of the shoulders 15, 16 (see Fig. 5), the breech slide G is set free and thereafter moves back independently of the barrel, which remains locked fast to the frame. The breech slide and breech block move back until the breech block, as usual, strikes the rear post 29 on the main frame. 45 From the instant of stoppage of the barrel, the further movement of the breech slide compresses the spring H, and upon the completion of the recoil movement the reaction of this spring presses the breech slide forward, and when the breech block D strikes 50 the rear end of the barrel, the notches 23 come into coincidence with the locking lugs 24, so that these lugs may rise, thereby setting the barrel free from the frame and 55 locking it again to the breech slide, so that

the barrel participates in the remaining forward movement of the latter, this movement being assisted by the stress of spring 17.

It is understood that in arms of this class the hammer J is set or cocked by being thrown back by the breech block (see Fig. 5), being held cocked by the sear K, which acts notwithstanding the retracted position of the trigger; and that the arm is not fired until the trigger is released and again pulled. It 75 is also understood that the empty shell is ejected at the end of the backward movement of the breech block D by the usual ejector 80 30. It is also understood that at the instant when the breech block is fully retracted, the magazine pushes up the uppermost cartridge into the cavity E in front of the breech block, so that upon the ensuing reactive 85 movement the breech block pushes the new cartridge into the barrel to reload the arm. 85 These features are so well understood that it is not deemed necessary to illustrate the mechanisms or their operation in any detail.

The present invention affords a very simple, convenient, and effective construction 90 for the control of the barrel in an automatic pistol of the sliding barrel type. This type has some advantages over the construction where the barrel is fixed to the main frame. It is desirable that the barrel be 95 made as light as possible, in order that its mass may not materially affect the recoil operation; and that the major part of the weight of the recoil-actuated parts be in the breech slide G and breech block D, which 100 move together. Thus, the sudden stoppage of the barrel at the end of its small fraction of the total movement is inappreciable, the force of the recoil acting mainly against the comparatively heavy mass of the parts G, D. 105

I am aware that a breech lock in the form of a slide having an oblique engagement with the main frame, has been employed to lock a sliding barrel to the breech block. In my construction the lock effects engagement 110 between the barrel and the breech slide, and has no direct relation with the breech block, so that no interference is afforded to the disconnection of the breech block from the breech slide for moving the block independently of the slide. The breech lock has the double function of locking the barrel to the breech slide when the latter is forward, and for locking it fast to the main frame 115 from the instant when in the recoil movement the barrel is unlocked from the breech slide, so that during the major part of the recoil movement the barrel becomes in effect fixed to the frame.

It will be understood that the details of 125 construction of the breech lock and its co-acting parts may be subject to considerable modification without departing from the essential features of the invention. In the construction shown, the breech lock is in the 130

form of a tubular member embracing the upright projection 20 of the barrel, having lateral engagement with the oblique slots in the frame, and having lateral lugs projecting to the exterior and engaging notches in the opposite skirts of the saddle-like slide G. These details, while desirable and preferable, are not essential in the broader aspects of the invention.

10 It will be observed that the locking lugs 24 are beveled on their lower front sides, and engage a beveled surface 31 (parallel with the grooves 27) forming the bottom of notches 32 in the sides of the frame, in which notches the lugs move obliquely between the position shown in dotted lines, and that shown in full lines, in Fig. 1. In the position shown in full lines, the lugs are fully seated in the notches, and at the same time have a close sliding engagement with the under side of the slide G, whereby the locking piece M is itself locked fast during the movement of the slide G and until the notches 23 again come into coincidence with it during the forward movement; consequently, the locking piece, by being held immovable, holds the barrel fixedly in its rearward position until released during the forward movement of the breech slide.

30 I claim as my invention:

1. An automatic pistol comprising a frame, a barrel slidable thereon, a recoil-actuated breech block, a breech slide overlying the barrel, detachably connected with the breech block, and a lock for detachably uniting the slide and breech block, combined with a breech lock normally uniting the barrel and breech slide and movable during the recoil movement to free the breech slide and permit the latter and the breech block to continue their recoil movement after the movement of the barrel has ceased.

2. An automatic pistol comprising a frame, a barrel slidable thereon, a recoil-actuated breech block, a breech slide overlying the barrel, and a breech lock normally uniting the barrel to the breech slide and movable during the recoil movement to free the breech slide and permit the latter and the breech block to continue their recoil movement after the movement of the barrel has ceased, and adapted also to lock the barrel to the frame during the period of its disconnection from the breech slide.

55 3. An automatic pistol according to claim 2, the breech lock, when unlocked from the barrel, engaged by a parallel portion of the breech slide, and adapted to be held thereby in position locking the barrel to the frame.

60 4. An automatic pistol according to claim 1, the frame having a recess making oblique engagement with the breech lock, which is

movable in said recess, and said lock having a lateral locking lug, and the breech slide having a notch engaged by said lug.

65

5. An automatic pistol according to claim 1, the breech slide having longitudinal sliding engagement with the frame and formed as a housing overlying the barrel and confining the latter to the frame, and the lateral portions of the slide having coacting engagement with the breech lock.

70

6. An automatic pistol comprising a frame, a barrel slidable thereon, a recoil-actuated breech block, a breech slide overlying the barrel, and a breech lock, the frame having an oblique slideway and the breech lock engaging therewith, whereby it is movable transversely of the barrel, said lock normally uniting the barrel and breech slide 80 and adapted during the recoil movement to free the breech slide.

75

7. An automatic pistol comprising a frame, a barrel slidable thereon, a recoil-actuated breech block, a breech slide overlying the barrel and confining the latter to the frame, the block detachably secured to the slide, and a breech lock normally uniting the barrel and breech slide and held in engagement with lateral portions of the slide, and adapted during the recoil movement to free the breech slide.

80

8. An automatic pistol comprising a frame, a barrel slidable thereon, a recoil-actuated breech block, a breech slide overlying the barrel, and a breech lock uniting the barrel and breech slide and movable during the recoil movement to free the breech slide, the frame having a recess making oblique engagement with the breech lock, whereby the latter is moved transversely to the barrel during the recoil movement.

90

9. An automatic pistol comprising a frame, a barrel slidable thereon, a recoil-actuated breech block, a breech slide having longitudinal sliding engagement with the frame and formed as a housing overlying the barrel, and a breech lock normally uniting the barrel and breech slide, the slide having a recess engaged by said lock, the lock adapted to disengage said recess during the recoil, and the slide having a prolonged parallel portion engaging said lock during the further recoil movement.

100

10. An automatic pistol according to claim 9, the breech lock adapted to lock the barrel to the frame during the period of its disconnection from the breech slide and held in position so locking the barrel by engagement with such parallel portion of the slide.

110

In witness whereof, I have hereunto signed my name.

EDWARD S. POMEROY.
